UNITED STATES PATENT OFFICE

BENJAMIN GILOWITZ, OF NEW YORK, N. Y., ASSIGNOR OF ONE-EIGHTH TO SAMUEL KRAVITZ AND ONE-FOURTH TO MORRIS BOUSEL, BOTH OF NEW YORK, N. Y.

HEEL LIFT AND ATTACHING MEANS THEREFOR

Application filed March 28, 1931. Serial No. 526,079.

The invention aims to provide a new and improved means for attaching heel lifts or taps of leather or leather substitutes, rubber or composition.

5 With the foregoing in view, the invention resides in the novel subject matter herein-after described and claimed, description being accomplished by reference to the accompanying drawings.

10 Fig. 1 is a vertical sectional view showing one form of lift attaching means.

Fig. 2 is a sectional view at right angles to Fig. 1, as indicated by line 2—2 of the latter.

15 Fig. 3 is a lower end elevation.

Fig. 4 is a disassembled perspective view of the lift and its attaching means.

Fig. 5 is a view similar to Fig. 1 but showing a different form of the attaching means.

20 Fig. 6 is a sectional view on line 6—6 of Fig. 5.

Fig. 7 is a lower end elevation.

Fig. 8 is a disassembled perspective showing the lift and the attaching means.

25 Fig. 9 is a vertical sectional view showing a still further attaching means.

Fig. 10 is a perspective view, disassembled and partly in section, showing the attaching means illustrated in Fig. 9.

30 Fig. 11 is a view similar to Fig. 9 but showing yet another form of the attaching means.

Fig. 12 is a disassembled sectional view showing the attaching means illustrated in Fig. 11.

35 Fig. 13 is a sectional view illustrating a still further variation of the attaching means.

Fig. 14 is a section on line 14—14 of Fig. 13.

40 Fig. 15 is a disassembled perspective view showing parts of the attaching means shown in Figs. 13 and 14.

Throughout Figs. 1 to 15, H denotes a wooden heel, L has reference to a leather heel lift or tap, and P denotes a metal dowel pin secured vertically in the heel.

45 In the construction shown in Figs. 1 to 4 inclusive, the lower end of the pin P projects downwardly from the heel H and is snugly received in an opening 30 in the lift L. The lower end portion of the pin P is formed with

a longitudinal slot or kerf 31 which is preferably somewhat curved or angular, and a flat nail 32 is tightly driven into said slot or kerf, said nail having a T-head 33 whose ends become embedded in the lift L when said nail is driven into place. When so driving the nail, the shape of the slot or kerf 31 so distorts said nail that it will remain tightly in place, and due to the fact that said nail cannot rotate, it holds the heel lift L against rotation.

55 In the construction shown in Figs. 5, 6, 7 and 8, the only substantial differences are that the pin P does not extend through the lift L, and the flat nail 34 which is driven into the kerf or the like 35, is provided with an ordinary rectangular head 36 which embeds in the lift when the nail is driven home.

60 In Figs. 9 and 10, the lower end of the pin P is formed with a bore 39 and with a lateral opening 40 from the upper end of said bore. A wooden plug 41 is snugly received in the bore 39, and a conventional clinch nail 42 is driven through the lift L into said plug to constitute the primary attaching means for 70 said lift. The upper end of the nail 42 clinches against the upper end of the bore 39 and turns laterally at 43 through the opening 40. To hold the lift against rotation, other nails 44, much smaller than the nail 42 may 75 be driven through said lift and into the heel.

76 In Figs. 11 and 12, the pin P is provided with a substantially cylindrical longitudinally curved or angular bore or the like 45 into which a conventional clinch nail 46 is driven, 80 said nail passing through the center of the lift L. Small nails 47 are employed to hold the lift against rotation.

85 In Figs. 13, 14 and 15, the lower end of the pin P is provided with a flat-sided, upwardly tapered kerf or slot 48 which snugly receives a wooden plug or wedge 49, and a conventional clinch nail 50 is driven through the lift L into said plug or wedge 49. Small nails 51 are used to hold the lift against rotation.

90 It will be seen that any of the attaching means so far described, is simple and inexpensive, allows quick and easy attachment of the lift at the factory, permits the repairman to easily remove a worn-out lift, and al-

lows him to attach a new lift with equal ease. In each instance, where the central lift attaching nail is flat, its flat form holds the heel and lift against relative rotation.

5 The lifts L so far mentioned, may be considered as formed of leather or some appropriate leather substitute having about the same qualities. Any of the attaching means described however, may be used to equal advantage with rubber or composition heels provided with appropriate reinforcements.

I claim:—

1. In a means for attaching a lift to a wooden heel, a dowel pin secured in the heel and projecting downwardly therefrom into an opening in the lift, the lower end of said dowel pin having a longitudinal recess, and a nail driven into said recess, said nail having a head projecting laterally beyond the dowel pin and countersunk in the lift.

15 2. In a means for attaching a lift to a wooden heel, a dowel pin secured in the heel and projecting downwardly therefrom into an opening in the lift, the lower end of said dowel pin having a longitudinal recess, and a flat nail driven into said recess, said nail having a T-head driven into the lift.

3. In a means for attaching a lift to a wooden heel, a dowel pin secured in said heel and having its lower end flush with the lower end of the latter, said lower end of said dowel pin having a longitudinal recess, and a central flat nail driven through the lift and into said recess, the head of said nail being embedded in the lift.

30 4. In a means for attaching a lift to a wooden heel, a dowel pin secured in said heel, said pin having a longitudinal recess in its lower end, a relatively soft plug snugly held in said recess, and a central fastener driven through the lift and into said plug.

45 5. In a means for attaching a lift to a wooden heel, a dowel pin secured in said heel, said dowel pin having a longitudinal bore in its lower end and a lateral opening from the inner end of said bore, a plug of relatively soft material snugly held in said bore, and a central fastener driven through the lift and into said plug, the inner end of said fastener being clinched through said lateral opening.

55 6. In a means for attaching a lift to a wooden heel, a dowel pin secured in the heel and having an upwardly tapered longitudinal kerf in its lower end, a tapered plug of relatively soft material snugly received in said tapered kerf, and a fastener driven through the lift into said plug.

60 7. In a means for attaching a lift to a wooden heel, a dowel pin secured in the heel and having a longitudinal flat-walled slot in its lower end, said slot opening through the lower extremity of said dowel pin and through opposite sides of the latter, and a

flat nail driven into said slot and having a head countersunk in the lift.

75 8. A heel-reinforcing metal dowel pin having a longitudinal flat-walled slot in its lower end, said slot opening through the lower extremity of said dowel pin and through opposite sides of the latter.

In testimony whereof I affix my signature.

BENJAMIN GILOWITZ.
